ATTORNEY.

UNITED STATES PATENT OFFICE.

JOHN W. BONE, OF OMAHA, NEBRASKA, ASSIGNOR TO J. B. AUTOMATIC TERMINAL MANUFACTURING COMPANY, OF OMAHA, NEBRASKA.

BATTERY TERMINAL CONNECTER.

Application filed February 3, 1928. Serial No. 251,689.

The invention relates to battery terminal connecters and has for its object to provide a device of this character comprising a contractible sleeve carried by a chambered body member, in the chamber of which is rotatably mounted a head carried by a bolt threaded through an arm of the sleeve and which bolt forms means for contracting the sleeve.

A further object is to provide a plug closure for the chamber of the body member, thereby allowing acid resisting material to be placed in the chamber, for instance hard oil, which will prevent sticking of the bolt.

A further object is to provide the plug with a chamber into which an electric conductor is received, thereby utilizing the plug as a connector.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a horizontal sectional view through the connecter.

Figure 2 is a side elevation of the connecter.

Referring to the drawing the numeral 1 designates a contractible sleeve adapted to encircle a battery terminal 2, and to be contracted into close binding engagement with the periphery of the terminal. One side of the sleeve 1 has formed integral therewith a body member 3 having a chamber 4 therein, and which chamber 4 is adapted to receive hard oil or other material which will prevent corrosion around the head 5 of the bolt 6 for preventing sticking of the bolt for instance so the sleeve can not be expanded or contracted. The bolt 6 extends through an enlarged aperture 7 in the body member and is threaded at 8 through the arm 9 of the sleeve 1, therefore it will be seen when a tool is placed on the head 10 of the bolt the arm 9 may be forced toward the body 1 for contracting the sleeve or away from the body 3 for expanding the sleeve, consequently sticking incident to corrosion of the bolt at its headed end 5 is obviated. The head 5 also forms a closure for the inner end of the aperture 7, thereby

55 preventing loss of material therefrom. The head 5 may be placed on the bolt 6 in any suitable manner after the bolt is in position and through the open threaded end 11 of the body member 3, and applicant does not limit himself in this respect.

Threaded into the threaded end 11 of the body member 3 is a plug 12, which forms a 60 closure for the chamber 4 and also serves as an additional function as a socket 13 for a conductor wire 14, therefore it will be seen it will only be necessary to provide the socket 13 in the plug 12, which is a relatively 65 simple operation. When it is desired to replace material in the chamber 4, it will only be necessary to unscrew the plug 12, which will allow ready access to the chamber and to the headed member, and it will also be noted 70 that where there is any tendency to stick, by having the aperture 7 larger than the outside diameter of the threads of the bolt 6, any sticking or jamming can be easily broken by 75 tapping on the bolt head 10.

75 From the above it will be seen that a battery terminal connecter is provided, which is simple in construction, provided with a chamber for the reception of corrosion resisting material, and the closure plug for the chamber 80 is utilized as a socket for the reception of a conductor wire, which may be secured therein in any suitable manner, for instance by soldering.

The invention having been set forth what 85 is claimed as new and useful is:-

1. A battery terminal connecter comprising a contractible sleeve, a bolt for contracting said sleeve, a body member having a chamber therein for the reception of an anticorrod- 90 ing material, a head carried by said bolt, said bolt extending through an aperture in the body member and said head disposed within the chamber, a closure plug threaded in the body member, and means whereby a conductor 95 may be attached to said closure plug.

2. A battery terminal connecter comprising a body member having a chamber therein, a bolt extending through an enlarged aperture in the body member, a head carried by said bolt and disposed within the chamber and forming a closure for one end of the aperture, a contractible sleeve carried by said body member, an arm carried by said sleeve in 100

spaced relation to the body member and through which the bolt is threaded, a closure plug for the chamber in the body member in axial alinement with the bolt and a conductor receiving socket in said plug.

3. A battery terminal connector comprising a body member having a chamber therein, a contractible sleeve carried by said body member, an arm carried by said contractible

sleeve, a bolt threaded through said arm and extending into the chamber of the body member, a head carried by said bolt in said chamber and a combined plug and connector socket threaded in said chamber.

In testimony whereof I hereunto affix my ¹⁵ signature.

JOHN W. BONE.
